UNITED STATES PATENT OFFICE.

ALLEN E. OSTRANDER, OF RIDGEWOOD, NEW JERSEY, ASSIGNOR TO UNIVERSAL DRAFT GEAR ATTACHMENT COMPANY, A CORPORATION OF ILLINOIS.

DRAFT-GEAR.

1,199,814.

Specification of Letters Patent. Patented Oct. 3, 1916.

Application filed February 15, 1912. Serial No. 677,677.

To all whom it may concern:

Be it known that I, ALLEN E. OSTRANDER, residing at Ridgewood, Bergen county, New Jersey, and being a citizen of the United States, have invented certain new and useful Improvements in Draft-Gears, of which the following is a full, clear, and exact description, such as will enable others skilled in the art to which it appertains to make and 10 to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a detail sectional plan view showing the parts in assembled relation. Fig. 2 is a detail sectional elevational view showing several parts in assembled relation.

The object of the invention is to provide in a single casting a draft gear yoke adapted 25 for use with several of the standard or patented friction draft gears now in use in the United States, such as the Westinghouse, the Sessions, the Cardwell and other friction draft gears, in each of which there are friction elements and springs, the present invention comprising in a unitary casting a rear follower and a yoke, of the same general design, adapted for use with either of such draft gears. It also contemplates the 30 adaptation of such draft gears for use as centering devices, to coat with the shank of a coupling with which the yoke of the present invention is to be connected by, preferably, a horizontally extending key connecting the yoke, and inclosed draft gear parts, with the coupler shank. To accomplish this latter function the yoke is 35 equipped with a front follower of novel design which will be substituted for the front followers now used with such draft gears. To facilitate assembling the several parts of such draft gears, and also to expedite the placement of the draft gears when in the yoke here illustrated, the forward part of 40 the yoke is provided with lugs or stops which

serve as abutments against which the front follower may rest and by which such follower is held in one direction.

It is preferred that the dimensions of the yoke shall be such that the distance between 55 follower stops on the draft sills shall be, say one eighth of an inch, greater than the distance between the front face of the front follower and the rear contacting face of the rear follower—thus permitting the assembled 60 draft gear parts and the yoke to be easily placed in position between the front and rear follower stops. This slight separation of co-acting followers and follower stops will be useful in placing the gear in 65 position, but is so slight as to be negligible in operation of the draft gear.

The front follower has forward extensions which extend at each side of the median line of the yoke which serve to center 70 the draw bar with reference to said front follower on the return movement of the draw bar from the extreme position under draft strains.

Instead of centering the coupler by the 75 aid of extraneous devices which lend to complication I prefer to make the draft gear, the yoke and the centering device function jointly, and severally each as heretofore to secure, in a single device, their several functions. Thus the draft yoke is a part of the draft gear and the forward or front follower is the compression element in my centering device and, without straining the yoke by reason of rocking the coupler shank, 80 against it, I spread the jaws of the yoke to permit all necessary radial coupler travel and utilize the front follower during such radial travel to compress the draft gear elements as may be necessary to cause said 85 draft gear to exert its full, or necessary, power to again center the coupler.

Referring to the parts of the improved yoke the rear follower is cast integral with the forwardly extending arms 2—2, of 95 which arms there are four, two of which are disposed at each side of the median line, and which arms may be said to terminate in vertical alignment with the studs 3, which studs are adapted to serve 100

as stops for the front follower 19 of the draft gear, and beyond these studs the arms 2 are connected by relatively V-shaped extensions 4, within which extensions the key 5, which unites the draft gear yoke with the shank 6 of the coupler, is adapted to rest, the coupler shank being transversely slotted for the reception of the key 5, as is, common in the art. It will be noted that the improved yoke is provided with vertical side walls 7, and with top and bottom horizontal walls 8-8, whereby there is provided a hood, which is adapted to serve as a receptacle for friction elements or coöperating parts of a friction draft gear, though it is to be understood that the said hood or pocket is not intended to be used as a friction element of such draft gear.

Extending vertically from the rear face 20 of the follower 1 are strengthening ribs 9, three in number being illustrated, although any suitable number may be used. It will be noted that the rear face 10 of the rear follower 1 is, except for the ribs 9 before indicated, a plane, and angular corners 11 are provided to permit a tight fit and surface contact against any rigid abutment as for example the rear follower stops 12, which are preferably applied as ordinarily applied and preferably riveted to the draft sills by through rivets. The arms 2 are wider at their rear ends than at their front ends, and are of sufficient width to serve as supports for movable elements of a friction draft gear supported on the lower pair of such arms, the top arms 2 being preferably identical in conformation with the lower arms, so that the yoke may be used with either face at the top. Beyond the lugs 3 the upper arms 2 diverge outwardly, as shown in the assembled view, so that the extensions 13 thereof pass almost in contact with the front follower stops 14, with the outer edges of the extensions 13 extending parallel with the inclined inner faces of such front follower stops, thereby providing a tapering recess or socket adapted to receive the coupler shank, which recess or socket is relatively narrow at its inner end 45 adjacent the front follower of the draft gear, and is considerably wider at its forward or outer end. The object of thus tapering the parts is to permit radial travel of the coupler upon the key 5 without impinging the arms 13 of the yoke, through which the key 5 passes to lock the coupler and yoke in operative relation.

The front follower 19 of the draft yoke rests normally in contact with the inner faces of the studs 3 before referred to, and is maintained in that position by the resilient coöperating parts of the draft gear under normal conditions. The front follower is of peculiar construction and is provided

at each side of the center line thereof with 65 a bracket 16 recessed in its forward face portion to receive the rear edge of the key 5 before indicated.

Owing to the coöperative positions of the yoke, coupler shank, key, front follower and 70 the brackets of the front follower, it will be observed that radial travel of the coupler will swing the coupler and the key 5. The key 5 substantially fills the transverse slot 75 in the coupler shank as indicated in Fig. 1, through which slot it is projected to connect the coupler and the yoke, in consequence of which said key moves with the coupler radially and longitudinally of the 80 coupler travel or transversely of the key substantially as if they were formed integrally. The key 5 is free to move rearwardly in the yoke. The two flat faces, the one on the draw bar and the other on the follower when moved apart by the angling 85 of the draw bar are forced into the original position by the resiliency of the spring rigging. As soon as the pressure, which caused the coupler to swing in one direction or the other, is relieved, the recoil of the draft gear parts will project the follower forward into contact with the pair of studs 3, which such angling movement caused it to leave during the radial travel of the coupler, thereby automatically centering the draw bar with 95 reference to the front follower. This would be impossible with a draft gear as ordinarily constructed in which the forward portion or jaws in transverse alignment with the coupler shank rest in close contact with such 100 coupler shank. Owing to the spread of the forward ends 13 of the arms 2 a sufficient clearance is permitted between such arms to permit all necessary and ordinarily allowable radial coupler travel. If the arms 13 105 are not placed in an angular position with reference to the longitudinal axis of the coupler, sufficient clearance will not be provided for radial travel of the coupler between such arms, and if the outer face of 110 these arms 13 is not angular with reference to the longitudinal axis, there will not be sufficient clearance between such arms and the draft sills for the front follower stops. The draft sills being spaced as required by 115 Master Car Builders' Association rules, 12 $\frac{1}{2}$ " apart, it is evident that to permit the described radial travel a close adjustment of parts is necessary. To reinforce the metal forming the arms 13, ribs 17 are cast 120 integral therewith, which ribs preferably extend a slight distance outwardly from, though integral with, the arms 13.

Spreading the arms 2-2, as shown in the plan-sectional view, leaves a clear space 13 125 between such arms, through which the operative parts of the draft gear may be inspected, and spacing the arms 2-2 verti-

cally, as shown in the side elevational view, there is provided a clear space through which may project the spring-bolt incident to draft gears of the friction type, which 5 utilize laterally projecting springs, and to permit the necessary amount of longitudinal travel of such spring-bolt, I prefer to cut the side walls 7, as shown in the side elevational view and form the front edge there- 10 of in a curved line, said side wall being longer at the top and bottom than at the middle.

In assembling the class of draft gears in the yoke here shown, which draft gears are 15 not equipped with laterally projecting springs adapted to extend beyond the draft sills, all the parts may be placed in position within the yoke, after which the yoke with inclosed draft gear may be lifted into position 20 between the draft sills, and in assembling and positioning draft gears in which the laterally projecting springs are utilized extending beyond the draft sills, the friction elements may be assembled within the yoke, 25 after which the spring rod may be projected through the sills, friction elements and yoke, and the springs subsequently applied.

While exact dimensions are not absolutely essential, it will be borne in mind that the 30 present invention is adapted for application to cars built in accordance with Master Car Builders' Association requirements, in which the distance between draft sills is fixed, as is also the distance between front and rear 35 follower stops attached to said draft sills, hence it is evident that a practical working condition is intended to be met, and not a mere theory of position of parts.

It will be observed that the end portions 40 of the key 5 are cut away at the corners 5^a, 5^b, so as to permit the key to be driven into position and fit closely between the forward ends of the extensions 16 of the front follower 19 and the rear inner faces of the 45 arms 13 within the loop formed therebetween so as to place the parts in such practical working condition that the forward extensions 16 will bear at all times against the key 5 and thereby serve to center the 50 draw bar with reference to the front follower and the draft sills as shown in Fig. 1 of the drawings.

What I claim is:—

1. In a draft gear, a yoke formed with 55 rear end, top and bottom members and having an opening in its side for the insertion transversely of a front follower plate, a front follower plate therein, and extensions on said follower plate to center the draw 60 bar with reference to the front follower on the return movement of the draw bar from the extreme position under draft strains.

2. In a draft gear, a yoke formed with 65 rear end, top and bottom members and hav-

ing an opening in its side for the insertion 65 transversely of a front follower plate, a front follower plate therein, and extensions on said follower plate to automatically center the draw bar with reference to the front follower on the return movement of the 70 draw bar from the extreme position under draft strains.

3. In a car construction, draft sills, a draft gear, a coupler, a yoke loosely connected with the coupler, a coupling member connecting coupler and yoke and free to move rearwardly in said yoke and a front follower 75 coacting with said member and the draft gear to center the coupler.

4. In combination, a yoke, a coupler with 80 lateral extensions connected with the yoke, a front follower and extensions on said follower adapted to bear against said lateral extensions whereby the front follower is 85 adapted to center the coupler.

5. The combination with draft sills and a coupler, of a draft yoke, a key connecting said yoke with said coupler, the yoke being formed of a single casting including stationary front follower stops, a front follower carried by said yoke and normally engaging said stops and having extensions forwardly of said stops adapted in certain positions to center the draw bar with reference to the front follower on the return 95 movement of the draw bar from the extreme position under draft strains, said key being freely movable in said yoke in one direction independently of said yoke.

6. In a car construction, draft sills, a 100 draft gear, a coupler and a yoke loosely connected with said coupler, the yoke having ends lapping the coupler and spaced therefrom diverging outwardly to permit radial coupler travel in the lapping portion 105 of the yoke, a transversely disposed key freely movable in one direction independently of said yoke, and resiliently controlled means having extensions adapted to automatically center the drawbar with reference to the said 110 means.

7. In a draft gear, a front follower having a recessed front end, a yoke having spaced forwardly directed divergent extensions between which the coupler is radially movable, a coupler key removably positioned in said extensions, and means on the front follower to automatically center the draw bar with reference to the front follower on the return movement of the draw bar from 120 the extreme position under draft strains.

8. In combination, a draft gear yoke formed as an integral casting and comprising a rear hood, top and bottom arms extending forwardly from said hood said 125 arms being spaced apart vertically and horizontally for the major portion of their length and terminating in a loop at each

side and stop lugs formed integral with said arms near their outer ends and intermediate said ends and the said hood.

9. In combination, a draft gear yoke formed as an integral casting comprising a rear hooded follower with forwardly extending spaced arms terminating in looped end portions and with stop lugs intermediate said hood and looped ends and a separately

formed follower adapted to rest against said lugs and extend within the loop parts of said yoke.

In witness whereof I have hereunto set my hand in the presence of two witnesses.

ALLEN E. OSTRANDER.
